UNITED STATES PATENT OFFICE.

JOHN T. MORGAN, OF CHARLESTON, WEST VIRGINIA.

HANGER FOR CONDUCTOR WIRES.

1,325,899.

Specification of Letters Patent.

Patented Dec. 23, 1919.

Application filed June 6, 1917. Serial No. 173,094.

To all whom it may concern:

Be it known that I, JOHN T. MORGAN, a citizen of the United States, residing at Charleston, in the county of Kanawha and 5 State of West Virginia, have invented new and useful Improvements in Hangers for Conductor-Wires, of which the following is a specification.

This invention is an improvement in devices of the type commonly employed for the suspension of trolley wires and other similar conductors.

One of the objects of the invention is to provide a combined hanger and clamp so arranged that the conductor may be supported without placing the insulating body under tension, but will be under compression alone. A further object is to provide a combined hanger and clamp composed of few parts 20 which may be quickly and easily assembled, or separated as desired, for the purpose of making repairs, substituting new parts and the like. A further object is to provide a combined hanger and wire clamp so constructed that the hanger may be readily aligned with the wire. A further object is to provide a device of the type referred to, constructed to reduce the chances of short circuiting, having means by which all of the 30 paths of possible short circuit are separated.

The invention will be hereinafter fully set forth and particularly pointed out in the claims.

In the accompanying drawing:—

Figure 1 is a side elevation of a hanger constructed in accordance with the invention. Fig. 2 is a top plan view thereof. Fig. 3 is a transverse section on the line 3—3, Fig. 2. Fig. 4 is a detail view illustrating 40 the swivel support. Fig. 5 is a sectional view illustrating a slight modification.

Referring to the drawing, 10 designates a body of insulating material, preferably porcelain, provided with chambers 11, located contiguous to opposite faces of the insulating body, said chambers being open at the bottom and also at their outer sides. The upper ends of the chambers 11 are connected by a channel 12, the portion of the 50 insulating body surrounded by said chambers and said channel, forming a supporting or suspension core 13. Extending transversely through the core 13, and passing between the chambers 11, is an opening 14, which registers with grooves 15, formed in the sides and top of the body 10.

The supporting member of the hanger consists of a metal band or casting 16, passed through the opening 14, and shaped so as to lie within the grooves 15, the free ends of 60 said band overlapping and being united by suitable means, as illustrated in Fig. 4. A rivet 17 is passed through the band 16 and the solid bottom of a nut 18, designed to engage a threaded supporting stud, the connection between the nut and the band 16, being such that the insulating body is swiveled or free to turn with respect to said nut.

The conductor suspension means comprises two arms 19, each having an angular branch 20, and a clamp portion 21, the angular portions 20 extending into the channel 12, the main portions of said arms being suspended within the chambers 11, with the 75 clamp portions extending below the core 13. The conductor wire 22 is clamped between the clamp portions 21, the necessary pressure being maintained by means of a bolt and nut 23, as illustrated in Fig. 3.

In practice, the band 16 is secured in position by being passed through the opening 14, and bent around the insulating body, after which the ends of the bands are attached to the nut 18, to provide the swiveled 80 connection above referred to. The angular ends 20, of the arms 19, are then inserted into the channel 12, by being passed in through the open bottoms and sides of the chambers 11. It will be readily understood 90 from the drawing that when the clamping portions 21, are drawn together, the arms 19 are caused to rock slightly on the core 13, until the angular branches 20 bear against the top of the channel 12, and in this manner said arms are locked against displacement. The arms 19 possess sufficient resilience to permit of the clamping action of the nut and bolt 23, and the swiveled connection with the nut 18 permits the block 100 10, and the parts secured thereto, to be turned into a position to properly align with the wire 22.

In Fig. 5 is illustrated a slight modification in which a single strap or band 25 is 105 employed as the suspension means, in lieu of the arms 19. In this form of the invention the ends 26, of the band are brought together, and clamp members 27, secured thereto by means of a bolt and nut 28, 110 by means of which arrangement the bolt and nut serve the double function of securing the

ends of the bands together and of providing the necessary clamping pressure.

From the foregoing it will be readily understood that by employing the hanger and suspension members in the relation shown and described, the insulating body is under compression while supporting the conductor, but never under tension, which is an important advantage in the art to which the 10 invention appertains. The relative arrangement of the supporting device and the suspension device is such that all paths of possible short circuit are separated, and said members are of such simple construction 15 that they may be readily assembled or separated, as may be desired.

In practice, should the roof which supports the screw engaged by nut 18 to sustain the device, be inclined, as is not uncommon, 20 the band 16 may be slipped around the body 10, and the arms 19 may be correspondingly shifted to compensate for the inclination and to suspend the conductor 22 in a central position.

Having thus explained the nature of the 25 invention, and described an operative manner of constructing and using the same, although without attempting to set forth all of the forms in which it may be made, or 30 all of the forms of its use, what is claimed is:—

1. A combined hanger and clamp of the character described comprising a body of

insulating material provided with chambers separated by an insulating wall and open at 35 the bottom, said body also having a diametrically disposed channel connecting said chambers at the top through said insulating wall, a supporting band passed through the insulating wall between the chambers and 40 below the channel, and at an angle to the latter, said band being passed over said insulating wall, a swiveled support for the band, and conductor suspension means located in said chambers and extending into 45 said channel.

2. A combined hanger and clamp of the character described comprising a body of insulating material provided with chambers separated by an insulating wall and 50 open at the bottom, said body also having a diametrically disposed channel connecting said chambers at the top through said insulating wall, a supporting band passed through the insulating wall between the 55 chambers and below the channel, and at an angle to the latter, said band being passed over said insulating wall, a threaded attaching member; a swivel passed through said band and connecting the same with said attaching member, and conductor suspension means located in said chambers and extending into said channel.

In testimony whereof I have hereunto set my hand.

JOHN T. MORGAN.
